UNITED STATES PATENT OFFICE.

ALVIN L. BAUHARD, OF BRISTOL, TENNESSEE.

MIDDLELINGS-PURIFIER.

SPECIFICATION forming part of Letters Patent No. 487,597, dated December 6, 1892.

Application filed March 30, 1892. Serial No. 427,031. (No model.)

To all whom it may concern:

Be it known that I, ALVIN L. BAUHARD, a citizen of the United States, residing at Bristol, in the county of Sullivan and State of Tennessee, have invented a new and useful 5 Middlings-Purifier, of which the following is a specification.

This invention relates to middlings-purifiers; and it has for its object to provide an 10 improved machine of this character which, while constructed with comparatively few working parts and therefore capable of being run with small power, at the same time is so constructed as to utilize the same air over and 15 over and to confine all the matter therein, so that the many disadvantages and inconveniences resulting from the use of dust-collectors and dust-rooms are avoided. The machine also provides for the thorough separation 20 of the lighter middlings and fluff from the heavier grain to be separated.

With these and many other objects in view, which will readily appear as the nature of the invention is better understood, the same 25 consists in the novel construction, combination, and arrangement of parts hereinafter more fully described, illustrated, and claimed.

In the accompanying drawings, Figure 1 is a vertical sectional view of a middlings-purifier 30 constructed in accordance with this invention. Fig. 2 is a horizontal sectional view of the same on the line 2 2 of Fig. 1. Figs. 3 and 4 are opposite end views showing the belt connections.

Referring to the accompanying drawings, A represents a suitable inclosing frame or casing, within which are located the various parts of the purifier. Within said casing are formed the opposite settling-chambers B and 35 B', respectively, adjacent to the sides of the casing and within the same and partitioned by the inner walls C from the large central collecting and settling chamber or compartment D. The opposite chambers or compartments are also provided with the inclined bottoms b and b', respectively, which lead to the discharge-openings E and F, from which the settling of the respective chambers may be spouted continuously or withdrawn when 40 desired. The central larger chamber D is also provided with the converging inclined bottoms D', which terminate in a conveyer-

box G in which revolves an ordinary screw-conveyer G', suitably geared with the other working parts of the machine and designed 55 to carry the fluff and flour settling in the chamber or bin D from without the machine. The opposite partition-walls C terminate short of the upper air and suction trunk H, through which the circulating air in the machine is primarily drawn. As stated, the said partition-walls C terminate short of the upper air or suction trunk H or at least the bottom h thereof, so that the several compartments may communicate with each other. 60 The chambers B' and D communicate directly with each other over the top of the partition-wall separating the same, while the opposite chamber B communicates with the central chamber D through the air-passage I, 65 formed between one of the walls C and the depending wall I', extending from one end of the bottom h of the air or suction trunk downward into the chamber or compartment B, so as to cause the air passing from the intermediate 70 chamber D to pass through the falling middlings and ascend therethrough before again finding its way into the upper air or suction trunk H. The bottom h of said air or suction trunk extends at one end only to 75 the point at which the wall I' depends therefrom, and thus forms a suction-passage J between the upper end of the wall I' and the inner side of the feeding-box K. The said feeding-box is provided with a cant bottom 80 k, leading to the discharge-opening k', opening into said suction-passage, the draft from which into said air or suction trunk being controlled by the valve L, working over the upper end of the suction-passage J, and by 85 suitably controlling the same is designed to accurately regulate the draft of air through the middlings.

Within the feeding-box K is located the hopper M, having the bottom escape-opening 90 m, within which works the feeding-roller N, and over which is secured the swinging automatic feed-regulating door O. The said door O has its lower swinging end working over and upon the feed-roller, and is connected by 95 means of the connecting-link o with the weighted controlling-lever o', pivoted at one end to said hopper, and which may be so adjusted as to accurately control the amount of

grain carried from the hopper by the feeding-
roller and into the feeding-box. Located in
the opposite end of the upper air or suction
trunk opposite to the feeding devices is the
5 fan-easing P, opening into said trunk and
causing the middlings-laden air to be drawn
therein by the revolving fan p revolving
within the same. The said fan-easing is pro-
vided with an elongated discharge-spout Q,
10 which projects a considerable distance into
the chamber or compartment B', so that the
middlings carried by the air through said
spout may have an opportunity to settle and
collect within said chamber or compartment,
15 while the air and the fluff and flour carried
therewith passes over the top of the partition-
wall into the central chamber or compart-
ment and is directed against the central baf-
fle-plate R, depending centrally within the
20 large central collecting and settling chamber,
into the bottom of which the fluff and flour
settles and is carried off by the conveyer G',
while the unburdened air passes out of said
air-passage I into the chamber B, from which
25 it again finds escape to the upper air and suc-
tion trunk, as indicated by the arrows.

A conveyer-box S extends across the bot-
tom of the upper air or suction trunk H and
is designed to receive the second separation
30 of middlings collected and deflected therein
by the valve T working thereover and suit-
ably regulated. The middlings are carried
from said box without the machine by the
conveyer U working in said box S. It will
35 be readily observed that the feeding-roller,
the upper and lower conveyers, and the fan
can be readily connected together, as illus-
trated in Figs. 3 and 4, by suitable belting,
and driven by the same power, so that the
40 machine can be easily operated.

Without further detailing the course of
the air-currents and the separations, which
are readily apparent, it will be readily ob-
served that there are four distinct separa-
45 tions. In the first place the heavier mid-
dlings, unaffected but purified by the air pass-
ing therethrough from the passage I, fall to
the bottom of the chamber B. The second
separation is effected in the air or suction
50 trunk by the valve T, and the separated mat-
ter falls into the conveyer-box S, while the
third and fourth separations are effected in
the chambers or compartments B' and D, re-
spectively, as will be readily noted.

55 The construction, operation, and many ad-
vantages of the herein-described middlings-
purifier are thought to be apparent without
further description.

Having thus described my invention, what
60 I claim, and desire to secure by Letters Patent,
is—

1. In a middlings-purifier, the combina-
tion, with the closed casing, of a series of col-
lecting or settling chambers or compartments
65 communicating with each other and arranged

side by side, a horizontal closed air or suc-
tion trunk extending across the top of the
casing above the upper open ends of the se-
ries of chambers or compartments and ter-
minating short of the casing at one side to 70
form a communicating passage with one end
compartment of the series, and a fan located
in said closed air or suction trunk and com-
municating therewith and provided with a
depending spout discharging into the oppo- 75
site end compartment of the series, substan-
tially as set forth.

2. In a middlings-purifier, the combina-
tion, with the casing, of the vertical parti-
tion-walls within said casing, separating op- 80
posite side chambers and a central collecting
and settling chamber, a horizontal closed air
or suction trunk located in the top of said
casing and having the bottom thereof above
the upper ends of said walls, a supplemental 85
wall depending from one end of the bottom
of said trunk adjacent to and parallel with
one of said partition-walls to form an air-pas-
sage between the same and said wall, a feed-
ing-box located within said casing opposite 90
and above the supplemental wall to form a
suction-passage opening into one end of said
trunk, a valve arranged at the upper end of
said passage, and a fan located in and com-
municating with said trunk and having a 95
spout depending into one of the side cham-
bers, substantially as set forth.

3. In a middlings-purifier, the casing, op-
posite chambers or compartments within said
casing, a larger intermediate chamber or com-
partment communicating with each of said 100
opposite compartments, a conveyer located
in the bottom of said intermediate compart-
ment, a closed air or suction trunk located
in the top of the casing above said compart-
ment or chamber and communicating with 105
one of said side compartments, a conveyer
located in the bottom of said air or suction
trunk, a valve working directly over said
conveyer within the trunk and arranged to 110
direct the lower portion of the current in the
trunk into the conveyer, and a fan discharg-
ing from said air or suction trunk into the
opposite side compartment, substantially as
set forth. 115

4. A hopper having a bottom escape-opening,
a feeding-roller working within said open-
ing, a swinging feed-regulating door working
over said opening and against said feed-roller,
a weight-controlled lever pivoted to said hop- 120
per, and a link connected with said lever and
said door, substantially as set forth.

In testimony that I claim the foregoing as
my own I have hereto affixed my signature in
the presence of two witnesses.

ALVIN L. BAUHARD.
